(57) **CLAIM**

The ornamental design for a load handling device as shown and described.

DESCRIPTION

FIG. 1 is a top view of an embodiment of a load handling device embodying the new design;
FIG. 2 is a bottom view thereof;
FIG. 3 is a first side view thereof;
FIG. 4 is a second side view thereof;
FIG. 5 is a back view thereof;
FIG. 6 is a front view thereof; and,
FIG. 7 is a front, first side, and top isometric view thereof.

1 Claim, 7 Drawing Sheets
